UNITED STATES PATENT OFFICE

2,224,122

HIGH FREQUENCY APPARATUS

Simon Ramo, Schenectady, N. Y., assignor to General Electric Company, a corporation of New York

Application November 30, 1939, Serial No. 306,951

5 Claims. (CL 250—36)

The present invention relates to high frequency electronic apparatus and has for its object the provision of an improved signal-generating system for use at frequencies so high that electron transit time considerations play a controlling part in the operation of the apparatus.

A more specific object of the invention consists in the provision of an improved system for generating frequency modulated signals.

Briefly stated, the invention utilizes the combination of two independent signal-generating systems coupled to a single electron stream by which they are adapted to be excited. The signals developed by the two systems are of different frequency, and each system is of such character as to be excited only upon the attainment of a particular velocity of the electron stream. Consequently, by varying the stream velocity between the values which respectively result in excitation of the two signal-generating systems, the output of the apparatus as a whole may be caused to vary from one frequency to another at a controllable rate. The ultimate effect, therefore, is to produce a frequency modulated signal.

The features which I desire to protect herein are pointed out with particularity in the appended claims. The invention itself, together with further objects and advantages thereof, may best be understood by reference to the following description taken in connection with the accompanying drawing in which Figure 1 illustrates diagrammatically a high frequency apparatus embodying the invention, and Figure 2 is a graphical representation useful in explaining the operation of the apparatus of Figure 1.

The apparatus shown comprises an electron beam tube having an elongated tubular envelope portion 10 and an enlarged electrode containing portion 11. The envelope is preferably constituted of a low-loss insulating material, such as glass, quartz, or the like.

The tubular envelope portion 10 is provided at one end with means, such as a known type of electron gun, for producing an electron beam. The combination which is shown for this purpose comprises a cathode 14, indicated in dotted outline, and a focusing cylinder 15 for focusing the electrons emitted from the cathode into a concentrated beam. The cylinder may either be connected directly to the cathode, as shown, or maintained a few volts positive or negative with respect to it. In order to accelerate the electrons to a desired extent there is provided an accelerating electrode 16 which is spaced

from the cathode and which may be biased to a suitable positive potential, say, several hundred volts.

After the electron beam issues from the cylindrical electrode 16 it is caused successively to traverse two ring-like electrodes 18 and 19 which define between them a region of substantially fixed beam velocity. Upon passage through the electrode 19, the beam is caused to impinge on anode 20, by which it is collected.

In the operation of the device described above, the electrodes 18 and 19 may appropriately be maintained at a potential several thousand volts above the cathode, while the anode 20 should be held at a somewhat lower potential for efficient collection of the beam. These potential relationships may be established by means of suitable voltage sources, which are conventionally represented in the drawing as batteries 22, 23 and 24. In order to maintain the beam in focus during its passage along the axis of the envelope one may employ a series of magnetic focusing coils (not shown), or other known focusing means.

The combination of elements so far described comprises means for producing a unidirectional beam of electrons. Outside the envelope there is provided a high frequency electrode arrangement adapted to cooperate with the beam.

The electrodes which make up the high frequency system include a series of sequentially arranged tubular conductive members which concentrically surround the envelope and which are respectively numbered 25 to 29, inclusive. The tubular members which bear odd numbers are conductively connected and are held at a common potential by connection to the positive terminal of the battery 24. The members 26 and 28, on the other hand, constitute independent electrodes which are capable of varying in potential at a desired frequency. For reasons which will be given hereinafter, the members just referred to are of different lengths, as will be apparent from inspection of the drawing.

The electrode 26 is associated with a tuned circuit and signal-transmitting means which are respectively represented by the combination of a condenser 32 and an inductance 33 and by an antenna 35. Similarly, the electrode 28 is associated with a circuit which includes a condenser 37, an inductance 38 and an antenna 39.

It is known that high frequency oscillations may be developed by means of an electrode combination such as that which is represented by the members 25, 26 and 27 provided proper cor-

relation exists between the length of the intermediate electrode (26) and the velocity of the electrons traversing it. In this connection, let it be assumed that a cyclically alternating potential is impressed between the member 26 and the members 25 and 27. It is clear that as a result of the potential gradients thus developed, electrons traversing the gap between members 25 and 26 are variously effected in velocity depending on the portion of the potential cycle at which they reach the gap. Consequently, the section of the electron stream passing through the member 26 at any given instant contains at various points along its length electrons of relatively high and relatively low velocity. The action of the faster electrons in catching up with the slower ones causes bunching of the electrons and produces charge density variations in the portion of the electron stream issuing from the member 26. Because of this fact, conduction currents of cyclically varying character are induced in the member 26 at its leaving end, so that an oscillating circuit appropriately connected to the member may be maintained in the excited condition. Referring more specifically to the arrangement of Fig. 1, self-sustained oscillations of the circuit 32, 33 may be developed provided the electron transit time through the member 26 is such as to correspond approximately to a quarter-cycle of the resonant frequency of the circuit, or to certain multiples thereof, including the fifth and ninth multiples.

It is apparent that for a fixed length of the member 26 the condition referred to in the preceding paragraph can be obtained only for the particular velocity of the beam which is adapted to provide the proper electron transit time through the member. Consequently, excitation of the circuit 32, 33 may be accomplished only provided the potential of the electrode 18 is adjusted to a critical value. If this value is materially departed from, oscillation of the circuit will cease.

Inasmuch as the length of the member 25 is shown as being materially different from the length of the member 26, it will be readily understood that the beam velocity which is required to cause excitation of the circuit associated with the former is different from that required to excite the circuit associated with the latter. Consequently, by changing the beam velocity from time to time it is readily possible to cause one or the other of the oscillating circuits to be selectively excited. Moreover, initiation of oscillation in one circuit will obviously be attended by cessation of oscillation in the other circuit.

In accordance with my present invention provision is made for varying the electron beam velocity between the value which is appropriate for excitation of the signal-generating system associated with the member 26 and that which is appropriate for excitation of the system associated with the member 25. In this connection, there is shown as one possible means of accomplishing the desired end, a manually operable switch or key 42 which is adapted to be shunted across the battery 23 so as to eliminate the effect of this battery in establishing the potential of the beam-velocity-determining electrode 18. A high resistance 43, connected in series with the battery and the switch, prevents the current drawn during closure of the switch from being excessive. In the intended condition of operation of the apparatus, the relationship of the batteries 23 and 24 is such that with the switch

42 in its open position, the beam velocity is appropriate to produce excitation of the electrode 28 and its connected circuit, whereas for the closed condition of the switch, the circuit associated with the electrode 26 is exclusively excited.

By alternately opening and closing the switch 42 the signal output of the apparatus as a whole may be caused to vary between the frequency of oscillation of the circuit 32, 33 and the frequency of oscillation of the circuit 37, 38. Consequently, the signal which is transmitted by the apparatus will be frequency modulated as indicated by the graphical representation of Figure 2. In this figure, the irregular line A 15 represents the transition of the apparatus from the condition in which it generates a signal of frequency f_1 , corresponding to oscillation of the circuit 32, 33, to a condition in which it generates a higher frequency f_2 , corresponding to 20 oscillation of the circuit 37, 38. This variation of frequency may be given intelligence-conveying significance by controlling the length of the time interval during which either signal frequency is generated. Thus, it is readily possible to adapt 25 the invention to a dot-dash system of intelligence-communication, such as is utilized in conventional code signalling practice. Receiving devices by which a signal of the type specified may be detected and translated are well known. 30

While I have described my invention by reference to a particular embodiment thereof it will be understood that numerous modifications may be made by those skilled in the art without departing from the invention. I therefore 35 aim in the appended claims to cover all such equivalent modifications as fall within the true spirit and scope of the foregoing disclosure.

What I claim as new and desire to secure by Letters Patent of the United States is:

1. In electronic signal-generating apparatus for use at frequencies so high that electron transit time considerations play a controlling part in the operation of the apparatus, the combination which includes means for producing an electron stream of controllable velocity, a pair of oscillating systems coupled to said stream, one of said systems being adapted to be excited by the stream to generate a signal of a first desired frequency upon the attainment of a first predetermined velocity of the stream and the other of said systems being adapted to be excited to generate a signal of a different desired frequency upon the attainment of a second predetermined velocity of the stream, and means for repeatedly varying the velocity of the stream between its first and second predetermined values, thereby to cause the signal output of the apparatus to vary between the said two desired frequencies. 40

2. In electronic signaling apparatus for use at frequencies so high that electron transit time considerations play a controlling part in the operation of the apparatus, the combination which includes means for producing a beam of electrons of controllable velocity, a series of conductive members successively coupled to the beam at spaced points along the beam path, the dimensions of certain of said members being such as to assure effective mutual reaction of the members and the beam for a first attainable beam 60 velocity, and the dimension of certain others of said members being such as to assure effective mutual reaction of the members and the beam for a second attainable beam velocity, an oscillating system including said certain members for de- 75

veloping a signal of a first desired frequency upon the attainment of the first-mentioned beam velocity, another oscillating system including said others of said members for developing a signal of a second desired frequency upon the attainment of the second beam velocity, and means for shifting the beam velocity between its said first and second values.

3. In electronic signaling apparatus for use at frequencies so high that electron transit time considerations play a controlling part in the operation of the apparatus, the combination which includes means for producing a beam of electrons of controllable velocity, a series of variously dimensioned conductive tubular members surrounding the beam at spaced points along its path, the axial dimensions of certain of said members being such as to assure effective mutual reaction of the members and the beam for a first attainable beam velocity, and the axial dimensions of certain others of said members being such as to assure effective mutual reaction of such members and the beam for a second attainable beam velocity, an oscillating system including said certain members, another oscillating system including said others of said members, and means for varying the beam velocity between its said first and second attainable values, thereby suc-

cessively and independently to excite the oscillating systems.

4. In electronic signaling apparatus for use at frequencies so high that electron transit time considerations play a controlling part in the operation of the apparatus, the combination which includes means for producing a beam of electrons of controllable velocity, means to control the velocity of said electrons to predetermined values, a first oscillatory means excitable to oscillation at one said velocity coupled to said beam and a second oscillatory means excitable to oscillation at another said velocity likewise coupled to said beam.

5. In electronic signaling apparatus for use at frequencies so high that electron transit time considerations play a controlling part in the operation of the apparatus, the combination which includes means for producing a beam of electrons of controllable velocity, means to control the velocity of said electrons to predetermined values, means to derive oscillatory current of one frequency from said beam at one said velocity and other means to derive an oscillatory current of a second frequency from said beam at a second said velocity.
